US00D735874S

(12) **United States Design Patent**
McClellan et al.

(10) **Patent No.:** US D735,874 S
(45) **Date of Patent:** ** Aug. 4, 2015

(54) **FLUID APPLICATION APPARATUS**

(71) Applicant: **SNAPPYSCREEN, INC.**, Locust Valley, NY (US)

(72) Inventors: **Kristen McClellan**, Locust Valley, NY (US); **Erkan Riza**, Sarasota, FL (US); **Aslan Leo Riza**, Sarasota, FL (US)

(73) Assignee: **SNAPPYSCREEN, INC.**, Locust Valley, NY (US)

(**) Term: **14 Years**

(21) Appl. No.: **29/487,968**

(22) Filed: **Apr. 14, 2014**

(51) LOC (10) Cl. **28-03**

(52) U.S. Cl.

USPC **D24/209**

(58) **Field of Classification Search**

USPC D24/158, 200, 209, 210, 231, 108, 232; 606/9, 33; 607/88-94; D25/106; 239/207, 208; 604/289, 290; 4/596, 4/615

(57) **CLAIM**

The ornamental design for a fluid application apparatus, as shown.

DESCRIPTION

FIG. 1 is a perspective view of a fluid application apparatus showing our new design;

FIG. 2 is another perspective view of the fluid application apparatus;

FIG. 3 is still another perspective view of the fluid application apparatus;

FIG. 4 is yet another perspective view of the fluid application apparatus;

FIG. 5 is a front view of FIG. 1;

FIG. 6 is a rear view of FIG. 1;

FIG. 7 is a side view of FIG. 1;

FIG. 8 is an opposite side view of FIG. 1; and,

FIG. 9 is a top view of FIG. 1.

1 Claim, 9 Drawing Sheets

FIG. 1

FIG. 2

FIG. 3

FIG. 4

FIG. 5

FIG. 6

FIG. 7

FIG. 8

FIG. 9
